The ornamental design of a revolving pulley case for an exercise machine, as shown and described.

DESCRIPTION

FIG. 1 shows a bottom view of a revolving pulley case for an exercise machine according to our new design;

FIG. 2 shows a front elevational view of the revolving pulley case shown in FIG. 1;

FIG. 3 shows a plan view of the revolving pulley case shown in FIG. 1;

FIG. 4 shows a right-hand side view of the revolving pulley case shown in FIG. 1;

FIG. 5 shows a left-hand side view of the revolving pulley case shown in FIG. 1;

FIG. 6 shows a rear elevational view of the revolving pulley case shown in FIG. 1; and,

FIG. 7 shows a perspective view of the revolving pulley case shown in FIG. 1.
